UNITED STATES PATENT OFFICE

LEWIS J. BAZZONI, OF SWAMPSOFT, MASSACHUSETTS, ASSIGNEE TO UNITED SHOE MACHINERY CORPORATION, OF PATERSON, NEW JERSEY, A CORPORATION OF NEW JERSEY

MANUFACTURE OF SHOES

Application filed August 24, 1923. Serial No. 659,150.

The present invention relates to the manufacture of shoes having Louis heels, or heels of that general type, and is herein illustrated as embodied in a machine especially adapted 5 for performing the operation of laying the heel breast leaf or split portion of the sole against the breast of a Louis heel after the heel has been attached to the shoe.

It is customary to cover the breasts of 10 wooden Louis heels after the heels have been attached to the shoes by applying to each heel breast a thin leaf or flap which has previously been formed by splitting the rear portion of the sole. Usually, for convenience 15 in fitting the heel seat or for other reasons, the sole is split along the shank to a point somewhat forward of the line where the base of the heel breast will be located. A coating of cement or other adhesive is applied to the 20 inner face of the leaf and thereafter the leaf is manually laid against the shank and the heel breast with the aid of a "bone" or other suitable implement for rubbing and pressing the breast leaf into place. After the 25 leaf has been thus manually laid in place, a heel breast clamp is employed to clamp the leaf firmly against the heel breast and hold it under pressure during the drying and setting of the adhesive. The laying of the leaf 30 manually as above described is a comparatively slow operation and considerable care is required if the leaf is to be laid smoothly throughout its entire area and the operation uniformly performed upon different shoes.

One object of the present invention is to 35 provide a practical machine for laying the heel breast leaf, and one which will perform that operation more quickly and efficiently than it can be performed by hand and in such 40 a manner as to insure uniform results upon different shoes.

With this object in view, one feature of the 45 invention consists in the provision, in a machine for use in the manufacture of shoes, of a novel organization of a yieldable pressure-applying member, and operating mechanism therefor constructed and arranged to press said member into engagement with the work, and then to move said member relatively to 50 the work to apply substantially rolling pres-

sure progressively along adjacent portions of the work. In the illustrated machine which is designed for operating upon a lasted shoe having a heel attached thereto and a sole formed with a leaf at the rear end thereof for covering the breast of the heel, there are provided a pressure-applying pad of rubber or other suitable yielding material shaped to conform under compression to the contour of the heel breast and adjacent shank portion 55 of the sole, and means for operating said pad first to move it into engagement with the forepart of said shank portion at its point of highest transverse convexity; then by continued movement of the pad in the same general direction to apply pressure progressively outward to the opposite lateral edges of the shank and rearward to and along a portion of the base of the heel breast; and thereafter to rock said pad about a substantially fixed 60 point adjacent to the base of the heel breast to cause the pad to apply pressure progressively upward along the heel breast to the tread face end of the heel, all for the purpose 65 of laying said leaf smoothly against the shank and heel breast. Preferably, the pressure-applying pad is secured to a carrier movably mounted upon a carrier support which is adapted for vertical swinging movement to lower the pad into engagement with 70 the shank portion of a lasted shoe suitably supported beneath the pad. After this downward movement of the pad has been effected to lay the leaf along the shank of the sole, a sliding movement in an arcuate path is 75 imparted to the pad carrier to move it relatively to the swinging carrier support for the purpose of rocking the pad to lay the leaf against the heel breast. The illustrated pad carrier and carrier support are operated by 80 means of mechanism controlled by a one-revolution clutch so that at each cycle of operations of the machine the pad is caused to perform a single leaf-laying operation and then to be retracted from engagement with 85 the shoe to permit the removal of the shoe which has been operated upon and its replacement by a shoe to be operated upon.

Other novel features of construction by 90 which the invention is carried out will be set 95 100

forth in connection with the following description of the illustrated embodiment of the invention.

In the accompanying drawings:

Fig. 1 is a view, in side elevation, of a machine embodying the present invention in what is now believed to be its preferred form;

Fig. 2 is a detail view, in front elevation, of the pad which is employed to lay the breast leaf;

Fig. 3 is a detail view, in front elevation, of a device which constitutes a back rest for the heel of the shoe being operated upon;

Figs. 4, 5 and 6 are detail views showing the positions of the leaf-laying pad relatively to the shoe in three successive stages of the leaf-laying operation;

Fig. 7 is a top plan view of the machine shown in Fig. 1, a portion of the framework being broken away to show the driving gears; and

Fig. 8 is a rear elevational view of the machine.

The illustrative machine comprises a support 2 for a lasted shoe, a back rest 4 for the heel of the shoe, and a movable pad 6 for laying the heel breast leaf. These parts are arranged in front of a hollow head or frame 8 within which is mounted mechanism for operating the leaf-laying pad. The head or frame 8 is secured to the upper end of a standard 10 and the pad-operating mechanism is driven by means of a motor 12 which is supported upon a bracket or shelf 14 that is adjustably secured to the rear of the head 8.

The support 2 for the lasted shoe consists of an upright arm formed with a rearwardly curved lower extremity which is rigidly secured to the front of the head 8. A last pin 16 surmounts the arm or support 2, adapting the latter to support a last such as indicated at 18 in Fig. 1. The last 18 is fitted within a shoe 20 having an attached Louis heel 22 and a heaf or flap 24 which has been split from the sole 25 of the shoe and is to be utilized to cover the breast of the heel.

To support the heel against the backward thrust of the leaf-laying pad 6, the back rest 4 consists of a roller of a diameter such that the curved face of the roll will substantially conform to the concave portion of the profile at the rear of the heel. The periphery of the back rest roll 4 is hollowed or caved in the direction of the axis of the roll, as shown at 26 in Fig. 3, to conform substantially to the horizontal or transverse convex curvature of that portion at the rear of the heel which is engaged by said roll. The roll 4 is mounted to turn freely upon a pin 28, the opposite ends of which are fixed in the arms of a yoke 30. The yoke 30 is mounted for a limited amount of vertical swinging movement to enable the back rest roll to adjust itself readily to heels of different

heights. To this end a stud 32, which extends rearwardly from the closed end of the yoke 30, is received within a split sleeve or socket member 34 and is rigidly but adjustably clamped therein by means of a binding screw 36 arranged to contract the sleeve about the stud. The sleeve or socket member 34 is arranged to rock about an axis perpendicular to the length of the stud 32 and to this end a bearing lug 38 depending from said sleeve is pivotally mounted upon a rod 40 which is parallel to the axis of the roll 4 and is supported at its opposite ends in bearings 42 formed on the frame 8. To limit the downward swinging movement of the back rest roll 4, a stop finger 44 projecting forwardly from the bearing lug 38 is arranged to engage an adjustable abutment in the form of a screw 46 which is threaded into the frame 8 and provided with a suitable lock nut 48 for binding it in adjusted position. After loosening the lock nut 48, the screw 46 may be turned to vary the lower limit of vertical swinging movement of the back rest roll and thus to vary the position of the latter when it is idle, i. e., when no shoe is present upon the support 2. This adjustment should be varied in accordance with the height of the heels to be operated upon, it being desirable that the roll 4, when idle, should be supported in a position lower than that which it is to occupy when engaging and supporting a heel and that it should be free to be lifted by contact with the heel of the shoe.

Being positioned as above described when a lasted shoe is being mounted upon the support 2, the roll 4 is first engaged by the rear portion of the heel at a point adjacent to the heel seat end of the heel and as the shoe is swung more or less in the general direction of the arrow 50 in Fig. 1, in the act of adjusting the shoe firmly upon the last pin 16, the roll 4 is caused to ride upwardly along the sloping rear face of the heel until it is finally elevated to the position in which it is illustrated in Fig. 1 and wherein it has adjusted itself to the contour of the vertically hollowed or concave portion at the extreme rear of the heel and serves very efficiently to support the heel against the backward thrust of the leaf-laying pad. By loosening the binding screw 36 and shifting the stud 32 longitudinally in its socket, the roll may be conveniently adjusted either forwardly or rearwardly in accordance with variations in the size and style of the heel to be operated upon, thereby adapting the roll rigidly and reliably to support the heel.

The leaf-laying pad 6 is made of yielding resilient material such as soft rubber and depends from a carrier 52 which overlies the rear of the shoe, the pad being rigidly secured to said arm in any suitable manner. The pad 6 is so shaped that when swung downwardly it may be brought initially into

contact with the shank of the sole at a single point only such as that indicated at 54 in Figs. 1 and 4, this point being located somewhat forwardly of the split portion of the shank and centrally of the transverse arch thereof. The movement of the pad 6 is then continued in the same general direction and thereafter it is rocked about its area of contact with the sole, as will hereinafter be described, so that the pad is compressed against the shank and heel breast. The shape of the pad is such that as it is thus actuated and compressed, it will function to apply pressure to the leaf so as to lay it progressively rearward along the shank and heel breast to the top-lift end of the breast and also progressively outward from the longitudinal median line of the shank to the opposite lateral edges thereof.

To enable the pad 6 to lay the breast leaf in the manner above described, the pad-carrying means and the actuating mechanism therefor are constructed and arranged as follows: The pad carrier 52 is of the irregular shape shown in Fig. 1, comprising a depending leg 60 to which the pad is secured and a rearwardly extending curved leg 62 which lies between a pair of supporting arms 64, the latter being arranged parallel to each other and pivotally mounted at their rear extremities upon spaced apart but axially aligned studs 66 that are fixedly secured in upward extensions 68 of the frame 8. The opposite end portions of the carrier leg 62 are slotted, as shown at 70, to receive bolts 72 which extend transversely through the supporting arms 64 and connect the latter to swing vertically in unison about the pivot studs 66. The slots 70 are elongated lengthwise of the carrier leg 62 and are of arcuate shape, the longitudinal center lines of the slots having the same radius and a common center of curvature which is located preferably somewhat below and at the rear of the heel breast when the pad 6 is depressed into its operative position in engagement with the sole. The bolts 72 extend loosely through the arcuate slots 70 and the above described shape and arrangement of the slots is such as to permit rearward movement of the pad-carrier 52 relatively to the carrier supporting arms 64 so as to rock the pad rearwardly after the leaf has been laid against the shank portion of the sole to cause the rear face of the pad to press the remaining unattached end of the leaf against the heel breast as will be hereinafter more fully described.

To move the pad 6 into leaf-laying engagement with the shoe, the supporting arms 64 are swung downwardly in unison about their axially aligned pivot studs 66 into the position shown in Fig. 4, and at the completion of the leaf-laying operation, the pad is returned to the position shown in Fig. 1 by a corresponding upward movement of said supporting arms. The supporting arms 64 are lowered and raised by cam-actuated means comprising a lever 74 and a connecting rod 76 which connects the forward end of said lever with the arms 64, the upper end of said rod carrying a yoke 78 the sides of which lie adjacent to the outer sides of the arms 64 and are pivotally connected therewith by the rearmost bolt 72. The lever 74 is fulcrumed at its rear extremity upon a fixed rod 80 and carries a cam roll 82 which rides in a groove 84 formed in a cam disk 86, the latter being fixed upon a cam shaft 88 that is journaled in suitable bearings in the sides of the frame 8. The cam shaft 88 is driven from the armature shaft 90 of the motor 12 through a train of gearing comprising a pinion 92 that is fast upon the motor shaft 90, an idler pinion 94 that is suitably mounted upon the frame 8, and a gear 96 which is loosely mounted upon the cam shaft 84 and is adapted to be connected therewith by means of a foot-controlled clutch 98.

As shown, the clutch 98 comprises a member 100, (Fig. 8) which partially encircles the shaft 88, and is provided with a pin 102 that is arranged to slide freely through a collar 104 fixed to the shaft 88. The pin 102 is adapted to be interposed in the path of movement of a pin or lug 106 carried by the hub of the gear 96. The clutch member 100 is normally maintained by a spring (not shown) in a position to connect the driving pulley operatively to the drive shaft. An inclined cam face 108 on the clutch member 100 operates, upon engagement with the upper end of a bell-crank lever 110, (see also Fig. 1) to disconnect the clutch member 100 and the shaft 88 from the driving gear 96. The lever 110 is mounted to rock upon a fixed pivot stud 112 and is arranged to be actuated by a treadle-rod 114, a suitable spring (not shown) being utilized which tends normally to hold the upper extremity of the bell-crank lever 110 in engagement with the cam face 108 to hold the driving clutch member 100 disengaged from the driving gear 96. The clutch 98 is actuated to start the machine by depression of a foot treadle (not shown) connected to the lower end of the rod 114.

As the supporting arms 64 swing downwardly to bring the pad 6 into engagement with the shank of the sole at the point 54, and further to apply pressure to the breast leaf progressively rearward along the shank and also progressively outward to the lateral edges thereof, the position of the pad-carrier 52 relatively to the supporting arms 64 remains unchanged. The pad conforms under compression to both the longitudinal concavity and the transverse convexity of the shank and functions to lay the breast leaf progressively rearward from the point 54 and also outward at both sides of the longitudinal median line of the shank so that the leaf is

subjected to what is, in effect, both a longitudinal and transverse rolling action. This is due partially to the path of movement of the pad relatively to the shoe and partially to the peculiar shape of the lower face of the 5 pad and the angle of presentation of said face to the sole whereby the pad is compressed into conformity with the contour of the shank as above described. It will be understood that although the action of the pad is not a wiping 10 or rubbing action the pad functions effectually to smooth out any wrinkles which may extend lengthwise or crosswise of the shank. The rear portion of the lower face of the pad 6 is shaped so as to conform readily under 15 compression to the concave curvature of the heel breast adjacent the shank. When the pad 6 has been depressed to the limit of its downward movement, it appears substantially as shown in Fig. 5, the breast leaf 24 being 20 held under pressure against the shank of the sole and upwardly to a certain extent along the curved base portion of the heel breast. It will be noticed, however, that the rear 25 face of the pad 6 is not in pressure-applying engagement with the greater portion of the heel breast and that the leaf has not yet been laid thereagainst.

After the pad has been depressed by the 30 above described downward swinging movement of the supporting arms 64, the pad-carrier 52 is moved rearwardly, relatively to the supporting arms 64, to cause the pad to be rocked backwardly about a substantially 35 fixed point adjacent to the base of the heel breast to apply the unattached end portion of the breast leaf to the relatively flat portion of the heel breast and to press it into the recess or scallop 116 at the tread face end of the breast. To effect this backward rocking of the pad, the 40 pad-carrier 52 is connected by a link 118 with the upper extremity of a cam lever 120 which is fulcrumed upon a rod 122 that is fixedly supported at its ends in the side members of the frame 8. At its lower end, the lever 120 45 carries a cam roll 124 which is received in a cam groove 126 in the cam disk 82. The lever 120 and cam groove 126 are so designed that while the pad 6 is moving downwardly into 50 engagement with the shoe, and at all times except while the pad is being rocked by the action of the cam lever 120, the axis of the pivotal connection between said lever and the link 118 is coincident with the common axis 55 of the pivot studs 66 about which the pad-carrier supporting arms 64 are swung. Thus the pad is free to move into its initial engagement with the shoe without its movement being influenced or modified by the connections 60 between the pad-carrier and the cam disk.

After the leaf has been laid against the shank portion of the sole, however, the pad is 65 rocked by the action of the cam lever 120 as above described to complete the leaf-laying

operation. This rearward rocking of the pad 6 moves it into the position shown in Fig. 6. In moving into this position the pressure of the compressed pad is concentrated at the portion of the shank close to the base 70 of the heel breast and along the adjacent curved portion of the heel breast. The angle between the rear face of the pad and the opposed breast face of the heel is gradually closed and the breast leaf is laid progressively upward along said heel breast to the tread face end thereof. The pad is laterally compressed as it is forced rearwardly against the heel breast and the yielding material of the pad is forced into the scallop or cavity 80 116 in the heel breast and the leaf is smoothly laid over the sides of said scallop. The rocking movement of the pad is insufficient to relieve to an undesirable extent the degree 85 of compression with which the leaf is held against the shank portion of the sole. After the leaf has been laid in the above described manner the pad 6 is rocked rearwardly to the position shown in Fig. 5 and thereafter is returned to the initial position shown in Fig. 90 1, thus completing the cycle of operations of the machine. Upon the return of the pad 6 to initial position, the clutch 98 is thrown out and the operation of the machine is arrested 95 to permit the removal of the shoe and the replacement of another in position to be operated upon.

It will be understood that to obtain satisfactory results from the use of the present machine a quick-drying cement should be 100 used upon the breast leaf. The length of time required for each cycle of operations of the machine, and consequently the amount of time the breast leaf is held under pressure against the shank and heel breast, is determined by the speed of the motor 12 and the ratio of the speed reducing gearing connecting the motor with the cam shaft. By changing the ratio of said gearing, the length of time consumed at each cycle of operations 105 may be varied to enable cements of different drying or setting properties to be successfully employed. In practice it may happen at times that the breast leaf will be curled 110 backwardly away from the shank and heel breast more or less when the shoe is positioned for the leaf-laying operation. In such cases it may be desirable for the operator preliminarily to wipe the free end of the breast leaf along the heel breast by hand sufficiently to 115 insure that the leaf will be so positioned as properly to be engaged and laid by the pad 6.

By reason of the above-described creeping or rolling of the pad 6 over the breast leaf the latter will be laid without being subjected to any frictional drag or pulling action such as would result from the wiping or rubbing of the pad over the breast leaf, and which would be liable to stretch or distort the 120

leaf and to injure its surface inasmuch as the leaf is moistened and softened by the cement before it is laid. The leaf will be laid smoothly and without injury thereto by means of the 5 pad 6 and the results will be uniform for the various shoes operated upon. Furthermore, by means of the present power-actuated machine the leaf-laying operation may be accomplished much more quickly than by hand.

10 The invention has been disclosed herein for illustrative purposes in an embodiment at present preferred but it is to be understood that the scope of the invention is to be determined from the appended claims rather 15 than from the foregoing description.

The invention having been described, that which is claimed and desired to be secured by Letters Patent is:

1. In a machine for operating upon a shoe 20 having a heel attached thereto and a sole formed with a leaf at the rear end thereof for covering the breast of the heel, means for supporting the shoe, and means comprising a pad adapted to conform under compression 25 to the contour of the surface of the heel breast for applying pressure in an upward direction progressively from the base to the top-lift end of the breast to lay said leaf smoothly against the breast.

30 2. In a machine for operating upon a shoe having a heel attached thereto and a sole formed with a leaf at the rear end thereof for covering the breast of the heel, means for supporting the shoe, and means for laying 35 the leaf against the shank and the heel breast constructed and operated to engage the shank at a point forward of the junction of the leaf with the sole and to apply substantially a rolling pressure progressively along 40 the leaf to the rear extremity thereof at the tread face end of the heel.

3. In a machine for operating upon a lasted shoe having a heel attached thereto and a sole formed with a leaf at the rear end thereof 45 for covering the breast of the heel, a last support, and means for applying the leaf to the heel breast by yielding pressure having component forces constantly tending to urge the leaf rearwardly toward the heel and upwardly towards the tread face end of the heel breast.

4. In a machine for operating upon a shoe, means for supporting the shoe, and power controlled means for laying a covering 55 against the shank and the heel breast, said means comprising a compressible pad having a face shaped to engage the shank initially along the longitudinal median line thereof and to apply pressure to the shank progressively outward from said line to the opposite lateral edges of the shank.

5. In a machine for operating upon a shoe, means for supporting the shoe, and means for laying a covering against the shank and the 65 heel breast, said means comprising a compress-

sible pad shaped and actuated to engage the shank initially at the point of highest transverse convexity at the forepart of the shank and to apply pressure to the shank progressively rearward and progressively outward 70 from said point.

6. In a machine for use in the manufacture of shoes, a yieldable pressure-applying member, and operating mechanism therefor constructed and arranged to press said member against a portion of a piece of work and then to rock said member relatively to the work to increase the area of pressure-applying engagement between the member and the 75 work.

7. In a machine for use in the manufacture of shoes, a yieldable pressure-applying member, means for operating said member to apply pressure to a portion of a piece of work, and means for rocking said member about its 80 area of contact with the work to effect the application of pressure to a greater area of the surface of the work.

8. In a machine for use in the manufacture of shoes, pressure applying means comprising a yieldable member conformable under compression to the surface contour of a piece of work and fixedly secured upon a movable support, and means for moving said support to press said member against the 90 work and then to rock said member about its area of contact with the work to effect the application of pressure to a greater area of the surface of the work.

9. In a machine for operating upon a shoe 100 having a heel attached thereto and a sole formed with a leaf at the rear end thereof for covering the breast of the heel, means for supporting the shoe, a yieldable pressure-applying pad, means for pressing said pad 105 against the leaf at the shank of the sole, and means for rocking the pad about its area of contact with the sole to lay the leaf against the breast of the heel.

10. In a machine for operating upon a 110 shoe having a heel attached thereto and a sole formed with a leaf at the rear end thereof for covering the breast of the heel, means for supporting the shoe, a yieldable pressure-applying pad adapted to conform under compression to the contour of the shank of the sole and of the heel breast, means for operating said pad to apply pressure to the shank of the sole progressively outward from its point of highest transverse curvature and rearward from the juncture of the leaf with the sole, and means for rocking the pad about a substantially fixed point on the surface of the sole to lay the leaf against the breast of the heel.

11. In a machine for operating upon a lasted shoe having a Louis heel attached thereto and a sole formed with a leaf at the rear end thereof for covering the breast of the heel, means for supporting the shoe, a yielding pad 120

adapted to conform under pressure to the contour of both the convex and concave portions of the breast of the heel, and means for actuating said pad to lay the leaf against the heel breast.

- 5 12. In a machine for operating upon a shoe having a heel attached thereto, means for supporting the shoe, a yielding pad having surfaces shaped to conform substantially to the shape of the shank of the sole and the breast 70
10 of the heel, and means for actuating said pad to apply pressure upwardly to lay a covering progressively lengthwise of said shank and heightwise of the heel breast.

- 15 13. In a machine for operating upon a lasted shoe having a heel attached thereto and a sole formed with a leaf at the rear end thereof for covering the breast of the heel, means for supporting the shoe, a compressible pad having surfaces shaped to conform under pressure to both the lengthwise and widthwise curvature of the shank of the shoe and to the contour of the heel breast, and actuating means for said pad constructed and arranged 75
20 to bring the pad initially into engagement 80
25 with the shank at the forward extremity of said leaf and thereafter to manipulate the pad to lay the leaf progressively along the shank and then outwardly along the heel breast.

- 30 14. In a machine for operating upon a lasted shoe having a heel attached thereto and a sole formed with a leaf at the rear end thereof for covering the breast of the heel, means for supporting the shoe, a pad having surfaces shaped to conform under pressure to both the lengthwise and widthwise curvature of the shank of the shoe and to the contour of the heel breast, means for supporting the pad above the shoe, means for swinging the pad downwardly to lay the leaf progressively from the forward to the rear extremities of the shank and against the adjacent curved portion of the heel breast, and means for rocking said pad about its area of contact 95
35 with the shoe to lay the free extremity of the leaf against the remaining uncovered portion of the heel breast.

- 40 15. In a machine for operating upon a shoe having a heel attached thereto and a sole formed with a leaf at its rear end for covering the breast of the heel, the combination of a shoe support and a yieldable pad relatively movable to apply pressure to the shank of the shoe sole progressively outward from 105
45 the center of the leaf and to apply pressure to the breast of the heel progressively upward from the base to the top lift end of the heel to lay a leaf on the heel.

- 50 16. In a machine for operating upon a shoe 110
55 having a heel attached thereto and a sole formed with a leaf at its rear end for covering the breast of the heel, a yieldable pad, a shoe support, and power-operated means for causing the pad continuously to move within a 120
60 vertical plane to effect operations of the pad 125
65

along the shank and upon the heel of a shoe on the support to lay the leaf along the shank of the shoe and the breast of the heel.

17. In a machine of the class described, the combination of a deformable pad, a shoe support, means for holding a shoe and an attached heel in a predetermined position upon the support, and power-operated means for causing the pad to operate along the shank of the shoe and breast of the heel to lay a 75
70 leaf thereon.

18. In a machine for operating upon a lasted shoe having a heel attached thereto and a sole formed with a leaf at the rear end thereof for covering the breast of the heel, means for supporting the shoe, a pad having surfaces shaped to conform under pressure to both the lengthwise and widthwise curvature of the shank of the shoe and to the contour of the heel breast, a carrier for supporting said pad above the shoe, an oscillating arm upon which said carrier is mounted with provision for relative movement of said carrier and arm to tilt the pad relatively to said arm, means for swinging said arm downwardly to lower the pad into engagement with the shank-covering portion of said leaf and progressively to lay the same lengthwise and rearwardly along the shank, and means for moving said pad carrier rearwardly relatively to said arm in an arcuate path having its center of curvature located below and to the rear of the heel breast to tilt the pad to press the free extremity of the leaf against the remaining uncovered portion of the heel 95
80
85
90
95
100
105
110
115
120
125

19. In a machine for operating upon a shoe having a heel attached thereto, means for supporting the shoe, means for laying a covering against the shank of the sole and the breast of the heel, and a back rest roll constructed and arranged to fit the curved surface at the rear of the tread face end of the heel, to support the heel against the thrust of the laying means, the roll being capable of adjusting itself to support effectively heels of different heights.

20. In a machine for operating upon a lasted shoe having an attached Louis heel, means for supporting the shoe, a device for laying a covering upon the breast of the heel, a back rest having a convex surface complementary to the concave profile of the rear of the heel adjacent to the tread face end thereof, to support the heel against the backward thrust of the leaf-laying device, and a mounting for the back rest enabling it to adjust itself to heels of different heights.

21. In a machine for operating upon a lasted shoe having an attached Louis heel, means for supporting the shoe, a device for laying a covering against the breast of the heel, a back rest shaped to conform to the curvature at the rear of the heel adjacent to the tread face end thereof supporting the 130

heel against the thrust of the laying device, and means for supporting the back rest constructed and arranged to permit adjustment of the back rest relatively to said means to 5 position it for use in connection with shoes of different sizes.

22. In a machine for operating upon a lasted shoe having an attached Louis heel, a last support, a device for laying a covering 10 against the breast of the heel, and means including a roller having its periphery shaped to conform to both the horizontal and vertical curvature of the rear of the heel adjacent to the tread face end thereof for supporting the heel against the backward thrust 15 of the laying device.

23. In a machine for operating upon a lasted shoe having an attached Louis heel and a sole formed with a leaf at its rear end 20 for covering the breast of the heel, a last support, a device for laying the leaf against the breast of the heel, a roller having its periphery adapted to conform to the curvature of the hollowed portion at the rear of 25 the heel for supporting the heel against the thrust of the leaf-laying device, and means for supporting said roller constructed and arranged to be engaged by the heel and raised into conformity with the hollowed portion 30 at the rear of the heel as the last is positioned upon its support.

24. In a machine for operating upon a lasted shoe having an attached Louis heel and a sole formed with a leaf at its rear end 35 for covering the breast of the heel, a last support, a device for laying the leaf against the breast of the heel, a roller having its periphery adapted to conform to the curvature of the hollowed portion at the rear of the 40 heel for supporting the heel against the thrust of the leaf-laying device, means for supporting said roller, a vertically swinging carrier for said roller constructed and arranged to enable the roller to be engaged by 45 the heel and raised into conformity with the hollowed portion at the rear of the heel as the last is positioned upon its support, and adjustable means for determining the lowermost position of the roller when no shoe is 50 supported by the last support.

In testimony whereof I have signed my name to this specification.

LEWIS J. BAZZONI.
